UNITED STATES PATENT OFFICE.

GEORGE R. SHERMAN, OF PROVIDENCE, RHODE ISLAND.

DRESS-FORM.

SPECIFICATION forming part of Letters Patent No. 424,230, dated March 25, 1890.

Application filed March 18, 1889. Serial No. 303,660. (No model.)

To all whom it may concern:

Be it known that I, GEORGE R. SHERMAN, of Providence, in the county of Providence and State of Rhode Island, have invented 5 certain new and useful Improvements in Dress-Forms, of which the following is a full, clear, and exact description, reference being had to the accompanying drawings, forming part of this specification.

10 This invention has reference to an improvement in the construction of dress-forms, by which the adjustment of the form can be more conveniently made, the whole dress-form more readily packed into a small compass, and the dress-form assume more nearly the desired outline, so as to support the dress in the same manner as it would be on the person wearing it.

To this end the invention consists in the 20 peculiar and novel construction of the actuating-slide, the peculiar and novel arrangement of the expanding-braces, the construction of the ribs forming the skirt portion of the dress-form, and the support, as will be 25 more fully set forth hereinafter.

In the drawings, Figure 1 is a view showing my improved dress-form expanded for use. Fig. 2 is a sectional view showing the standard with its longitudinal groove and the 30 operating sliding block. Fig. 3 is a sectional view showing the upper and lower sliding block, the method for securing the hinged braces, and the locking-pin. Fig. 4 is a view of the support of the standard, showing the 35 legs folded.

In the drawings similar numbers of reference designate corresponding parts throughout.

Dress-forms are now largely used for draping the skirts at the home of the customers instead of draping them on the person. For this purpose it is essential that the dress-form can be packed into a small space convenient to be carried. It is also essential 45 that the dress-form shall be of the form or outline demanded by the fashion, which consists in artificial extensions of the human form. The dress-form shown in Fig. 1 is constructed to correspond to the present fashion, 50 in which the skirt is required to fall in front

close to the figure and expand in the rear, so as to extend considerably beyond the figure. To this end I use in my improved dress-form braces of different lengths to produce the desired outline in the dress-form.

Referring to the drawings, 5 indicates the post forming the support of the dress-form, and 6 the legs hinged to a sliding block secured to the post 5 by the clamp-screw 8.

7 indicates a plate secured to the lower end 60 of the post 5. This plate 7 is provided with three openings, into which the lower end of the legs 6 enter when the same are folded, as is shown in Fig. 4. In this position they are secured by clamping the sliding block to the 65 post 5 by means of the clamp-screw 8. The post 5 is provided at the upper end with the tube 9, forming a socket in which the standard 10 is supported and in which it can turn. The standard 10 is provided with the longitudinal groove 11. The sliding blocks 12 and 13 are provided with feathers, which enter the groove 11, so that the braces are held against independent rotation. In a dress-form in 70 which irregular expansion is to be produced 75 it is essential that the braces retain their positions, so as to expand the ribs in the desired direction. The whole dress-form can be rotated, as the standard 10 is free to rotate in the socket 9. The vertical ribs 14 are supported by the braces 15 near the bottom and the braces 16 at the hip portion of the dress-form by means of the braces 17, extending 80 from the sliding block 13 to the braces 16, and thus expanding the same in the same manner 85 as an umbrella is usually expanded. The sliding block 13 is provided with the spring-catch 18, having at one end a pin which enters a hole or depression in the groove 11 of the standard 10. The fastening 19, (shown in Fig. 90 3,) consisting of a wire having an eye to be used as a handle at one end, may be used as a holding-pin on the sliding blocks 12 and 13, and a coiled spring may be used to hold the locking device 19 in place. The braces are 95 all hinged in a ring made of a strip of metal, the sides of which are slotted, so as to produce a number of projections. These are turned over the center of the strip so that their ends nearly meet. A wire is now passed through 100

the braces and twisted together at the two ends, so as to hold the ends of the braces in the spaces between the turned-over projections, as is shown in Figs. 2 and 3.

- 5 The skeleton of the dress-form is made entirely of wire, so as to be as light as possible. To give it the desired stiffness, the wires are bent as follows: The vertical ribs 14 are made of one piece of wire, the one end of which is 10 first bent at the lower end 20. Then at the point 21 it is bent in a double bend to form the opposite side of the vertical rib. At 22 it is again bent to cross over to the first side. At the upper end it is bent so as to extend upward 15 behind the belt-band 24, thence over the belt-band to its lower edge, where the wire is bent and carried again upward, then bent over the upper edge of the belt-band 24, down behind the same, and thence parallel 20 with the first wire to the point 22, where it is bent across the first bend to the opposite side of the vertical rib and carried down to point 21, where the wire again crosses over the previously-formed bend and extends down to the 25 end which is bent to meet the beginning of the wire. The two ends are secured by the metal clamp-piece 25. The vertical ribs are stiffened by the cross-ribs formed of a piece of wire having a loop formed at its middle. 30 The ends of the wire of the cross-braces 26 are secured by bending around one of the wires of the vertical ribs 14 below the point 21, so that in folding the dress-form the ends can slide on the wire of the vertical ribs. The 35 braces 16 are bent at their inner ends to receive the wire by which they are secured in the sliding block. The wire forming the braces 16 is again bent about midway to form an eye to receive the braces 17, and at their outer 40 ends the wires forming the braces 16 are bent over and around the wires of the vertical ribs 14 and the loop of the cross-ribs 26 at the point 22. The ends of the braces 15 are also secured in the sliding block 12 by bending each of the

ends to form an eye, through which the wire 45 securing them to the slide passes, and by bending the outer end over and around the wires of the vertical ribs where they cross at the point 21.

By thus constructing the dress-form of wire 50 and crossing and bracing the same a durable, light, and cheap dress-form is produced that can be readily carried from place to place and quickly set up for use.

Having thus described my invention, I 55 claim as new and desire to secure by Letters Patent—

1. In a dress-form, the combination, with the standard, the sliding blocks, and the radial braces, of the vertical ribs, each constructed 60 of one length of wire doubled at the upper end and formed into a hook, the two side wires of each rib extending each from one side to the opposite side of the rib through the eyes of the braces, and the ends of the wire at the 65 lower end of the rib secured together by a clamp, as described.

2. The combination, in a dress-form, with the standard, the sliding blocks, and the ribs 14, constructed of a single wire, as described, of 70 the braces 15 and 16, individually of unequal length, so as to extend the dress-form near the bottom and at the hips unequally, as described, their outer ends encircling the wires of the ribs, and the sliding block 13, the braces 17, 75 and spring-catch 18, as described.

3. The combination, in a dress-form, with the standard provided with the groove 11, the sliding blocks, and the radial braces 15 and 16, of 80 the ribs 14, constructed of a single wire, as described, and the cross-braces 26, secured to the outer ends of the braces 16 and to the wires of the ribs 14 below the braces 15, as described.

GEORGE R. SHERMAN.
